TABLE OR THE LIKE

Berry C. Collins, Tallahassee, Fla.

Application April 29, 1955, Serial No. 35,740

Term of patent 14 years

(Cl. D33—14)

FIG. 1.

FIG. 2.

Figure 1 is a perspective view of a table or the like showing my new design; and

I claim:

The ornamental design for a table or the like, as shown.
